VALVE BAG WITH PASTED END CLOSURE

Harry E. Lee, Pensacola, Fla., assignor to St. Regis Paper Company, New York, N.Y., a corporation of New York

Application March 9, 1956, Serial No. 570,522

1 Claim. (Cl. 229—62.5)

This invention relates to valve bags of the type having an end closure formed of pasted flaps, that is to say, with an inturned corner flap at each corner and with overlying side flaps pasted with respect to one corner flap, and with a valve opening provided between the other corner flap and the overlying side flaps. Such bags are formed of paper or the like sheet material which may sometimes be laminated with other material to reinforce same or to render same moisture-proof or capable of resisting deterioration by reason of chemically active materials contained in the bag. Usually, but not necessarily, the bags of this invention are formed of a plurality of plies of the sheet material.

It has often been the practice to insert a flexible sleeve or supplemental sheet in the valve of such bags to extend inwardly beyond the valve lip at the inner end of the corner flap so that such sleeve or sheet will be collapsed or pressed by the contents of the bag when filled up against the interior of the top of the bag for more securely closing the valve against leakage and sifting out of the contents. It has also been the practice so to secure such sleeve or supplemental sheet to the valve lip that the latter will be thrust up against the top of the bag along with the sheet or sleeve. Despite numerous different expedients of this nature which have been used to obtain more secure and dependable closing of such valves, it is possible for some material, particularly if of a granular nature, to sift out. While this can largely be overcome by providing an outwardly protruding sleeve adapted to be tucked into the valve after filling the bag, yet such tuck-in type sleeves have to be carefully and manually tucked in by the workman who operates the automatic filling machine and this substantially reduces the speed and increases the cost of filling the bags.

With the present invention, the above difficulties are quite surprisingly and effectively overcome by using an inwardly directed valve sleeve so secured in place in the valve that in effect a pocket will be provided between the inner portions of the valve lip and portions of the sleeve material thereabove which are thrust up against the top of the bag when filled. Such pocket has its open end directed inwardly of the bag and thus when the bag is filled and bounced off from the filling machine spout, the material in the bag will thrust the greater part of the sleeve firmly up against the inside of the top of the bag, for effectively collapsing and closing the sleeve, and a mass of such material will be thrust into such pocket, such mass preventing the valve lip from being pushed up along with the collapsed sleeve and serving in effect as a wedge between the valve lip and the collapsed sleeve portions thereabove and acting thereafter to hold the outer portions of the sleeve collapsed in secure valve-closing condition.

If at least portions of the valve lip of such a construction are made relatively stiff as by pasting a plurality of plies thereof together without pasting same with respect to the collapsible sleeve portions thereabove,

2

then the closing effect due to such pocket will be especially effective.

Preferably the sleeve in accordance with the invention is made at its outer end with a folded-over portion forming an inwardly directed cuff and the outer surface of this cuff is pasted to the inside wall surfaces in the valve opening so that the pocket forms between such cuff and the adjacent portions of the sleeve per se. The material of such cuff at this inner end may, if desired, be continued and folded outwardly to the outer end of the sleeve and thence again inwardly inside the sleeve for some distance whereby the outer portions of the pocket will have at least two plies.

Other and more specific objects, features and advantages of the invention will appear from the detailed description given below, taken in connection with the accompanying drawings which form a part of this specification and illustrate by way of example the present preferred embodiment of the invention.

20 In the drawings:

Fig. 1 is a perspective view of the valve corner of a bag made in accordance with the invention;

Figs. 2 and 3 respectively are sectional views taken substantially along lines 2—2 and 3—3 of Fig. 1; and Fig. 4 is a perspective view of a preferred form of sleeve adapted for use in accordance with the invention.

Referring now to Fig. 1 in further detail, a multi-wall bag is here shown at 10 having an inturned valve corner flap 11, with overlying side flaps of conventional form as at 12 and 13. The valve sleeve is indicated at 14 and shown in further detail before its insertion in Fig. 4.

As shown in Fig. 4, the sleeve may comprise a flattened tubular element formed at its outer end with a folded-over cuff 15, which, when inserted in the bag, is directed inwardly of the valve. The upper surface of the cuff and under surface areas as at 16 insofar as same contact with the corner or side flaps in the valve, are adapted to be pasted to the latter. The areas on the inside of the cuff are free from pasting to the sleeve per se, so that a pocket opening inwardly of the bag is formed as indicated in Figs. 3 and 4. The sleeve may be formed by taking a suitable area of sheet material and folding it over to form the flattened tube as shown and with the folded-over edges overlapped and glued together as at 17 (Fig. 2). The surface of the sleeve which is to be the undersurface of the inner end thereof in the bag, may, if desired, be slit as indicated at 17a, such slit as shown being at a slightly angular position permitting the edges of the slit to overlap somewhat without wrinkling in case pressure is applied to the upper face areas of the filled bag tending to compress the sleeve edgewise. Various other forms of slits well known for such valve sleeves may be used, if desired. While ordinary flat kraft paper may be used as the sleeve material, in some cases it may be preferred to use a relatively flexible laminate of two thin sheets of paper for example with a thin interposed asphalt layer therebetween or a sheet of paper coated with a film of polyethylene or other moisture-proof material may be used as is well understood in the art of manufacturing bag valve sleeves.

The sleeve may be inserted in the bag valve during the operation of bottoming the bag by the same type of automatic operations heretofore customary for inserting sleeves in pasted end bags. That is to say, the cuff 15 in this case may have adhesive applied thereto or the bag flap surfaces which are to contact with the cuff may have sufficient adhesive applied thereto so that when the sleeve is put into place, it will remain lodged with its outer end affixed and sealed with respect to the inside wall portions of the valve. Bags in accordance with the invention may be filled on automatic filling machines in

the same manner as heretofore accomplished simply by placing the bag on the filling spout of the machine with the spout extending into the sleeve. And when the bag is filled and is dropped off or bounced from the region of the filling spout onto a conveyor for example, the material in the bag will be thrust up against the interior of the top of the bag causing the inner portions of the sleeve to become collapsed as indicated at 20 in Fig. 3. This will cause the upper end of the bag to arch upwardly somewhat including the portions as at 21 which are located above the valve lip shown at 22 in Fig. 3. Consequently a pocket as indicated will be formed into which a mass of the material will immediately find its way, thereafter acting in effect like a wedge preventing the valve lip 22 from flexing upwardly and keeping the sleeve portions as at 21 firmly collapsed even to the outermost portions as at 23 which will be exposed outside the valve.

It would normally be expected that when the material in the bag forces the inner portions of the sleeve up to collapsed condition, the valve lip 22 would similarly be forced up against the top of the bag, thus preventing the opening of any pocket for the reception of material as above described. In fact heretofore so far as is known, it has been the universal practice so to secure the valve sleeves in such valves as to insure that the valve lip areas would be pulled or forced up against the top of the bag, it having been supposed that such a result was essential to good closing action of the valve. However, extensive tests have shown quite surprisingly that if the sleeve is so secured as above explained as to permit the pocket to be formed, then invariably the pulverulent or granular material in the bag will enter and more or less fill such pocket and therefore afford the above-explained wedging effect for firmly collapsing and closing even the outermost portions of the sleeve.

Although a preferred embodiment of the invention is herein disclosed for purposes of explanation, various modifications thereof, after study of this specification, may be apparent to those skilled in the art to which the

invention pertains. Reference should accordingly be had to the appended claim in determining the scope of the invention.

What is claimed and desired to be secured by Letters Patent is:

In a valve bag of the type having an end closure formed of corner flaps and adhered overlying side flaps and with one of the inturned underlying corner flaps forming a valve lip, said side flaps joining with corner flaps along 10 diagonal fold lines, a sleeve positioned in the valve and normally flatwise against the inside of the top of the bag when empty, such sleeve having flexible portions protruding inwardly of the bag substantially beyond such lip and adapted to be pressed up against the inside 15 of the top of the bag by material therein when filled, the outer end portion of the sleeve being formed with a cuff directed inwardly of the bag, a part of the cuffed portion of the sleeve extending outwardly of the bag corner in exposed position beyond said diagonal fold 20 lines, exterior portions of said cuff being secured and sealed with respect to the interior walls of the valve, a pocket thereby being provided when the bag is filled, between the cuff and other portions of the sleeve which are adapted to arch upwardly together with the top of the bag, such pocket being open to the interior of the bag for receiving a mass of the material filled therein, whereby such mass will retain the sleeve portions thereabove up in collapsed valve-closing condition and with 25 the valve lip portions spaced therebelow.
